CLAIM

The ornamental design for footwear, as shown and described.

DESCRIPTION

FIG. 1 is a front perspective view of footwear showing my new design, with the collar of the footwear in an upright position;

FIG. 2 is a front view thereof;

FIG. 3 is a back view thereof;

FIG. 4 is a left side view thereof;

FIG. 5 is a right side view thereof;

FIG. 6 is a top view of the footwear, with the collar of the footwear in a folded-over position; and,

FIG. 7 is a bottom view thereof.

The broken lines in the figures illustrate portions of the footwear that form no part of the claimed design.

1 Claim, 7 Drawing Sheets
